STEAM LOCOMOTIVE BOILER

Charles D. Barrett, Altoona, Pa.

Application September 29, 1942, Serial No. 460,074

12 Claims. (Cl. 110—61)

1 This invention relates to improvements in steam locomotive boilers.

In the usual operation of a steam locomotive, air for combustion of said fuel is supplied by forced upward draft through the grate of the firebox created by suction in the flue tubes by discharge of exhaust steam from the engine cylinders through the exhaust nozzle and into the locomotive stack. The combustion rates are much higher in locomotive boilers than in stationary boilers, and since the whole of the air supply for combustion in locomotive boilers is ordinarily drawn up through the grate, the velocity of the air passing through the grate and the fuel bed thereon is very high. As a result, the smaller particles of coal are picked up from the fuel bed by the draft and discharged from the stack either unburned, or only partially consumed. The amount of coal wasted in this way is negligible when the locomotive boiler is worked at its lowest rate, but at the maximum rate when the velocity of the air for combustion is correspondingly high, the amount of fuel wasted may be as much as 40% of the total fuel fired. It has long been recognized that the ideal way to burn coal in a locomotive boiler is to supply part of the air for combustion above the fuel bed, and attempts have been heretofore made to increase the combustion efficiency of the boilers by employing power blowers or steam jet blowers to force part of the air into the firebox above the grate. In all of these attempts, however, live steam from the locomotive boiler was used to actuate the power blowers or the steam jet blowers, and therefore increase in the combustion efficiency was obtained only at the expense of the live steam output of the boiler. Other attempts have been made to increase the combustion efficiency of locomotives by allowing air to be drawn into the firebox under the influence of the vacuum within the firebox without using power blowers or steam jets. In such attempts, the quantity of air drawn in above the grate was relatively small, the air entering at such low velocity that the mixing of such air and combustible gases was necessarily very poor. Consequently the increase in the combustion efficiency so obtained was not large enough to result in any measurable saving in fuel, although such arrangements have been advantageous in reducing the quantity of black smoke discharged from the stacks of the locomotives.

My invention is directed toward overcoming the above drawbacks, that is to say, it has for its chief aim to insure more complete combus-

2 tion of the fuel in locomotive boilers without necessitating the use, either directly or indirectly, of live steam from the boiler. This objective I realize in practice as hereinafter more fully disclosed by diverting part of the waste steam which is ordinarily exhausted from the engine cylinders and released into the locomotive stack to inject additional combustion-supporting air into the firebox above the grate and thereby reduce the amount of air concurrently drawn in from beneath the grate under forced draft induced by that portion of the exhaust steam which passes through the exhaust nozzle and out of the stack. Under these conditions the velocity of combustion gases when passing through the fuel bed is considerably decreased so that the draft is not strong enough to carry away the smaller particles of the coal which therefore remain on the grate until completely consumed.

20 Other objects and attendant advantages will appear from the following detailed description of the accompanying drawings; wherein

Fig. 1 is a more or less diagrammatic view in side elevation, of a locomotive conveniently embodying my invention.

Fig. 2 is a fragmentary detail view looking as indicated by the angled arrows II—II in Fig. 1, and showing the rear end of one of the engine cylinders of the locomotive.

30 Fig. 3 is a fragmentary detail section taken as indicated by the angled arrows III—III in Fig. 2.

Fig. 4 is a fragmentary view showing the rear or firebox end of the locomotive boiler in side elevation.

35 Fig. 5 is a cross-sectional view of the boiler at the firebox end taken as indicated by the angled arrows V—V in Figs. 1 and 4.

Fig. 6 shows the rear end of the boiler in longitudinal section.

40 Fig. 7 is a large scale detail view in end elevation of one of the air injecting nozzles.

Fig. 8 shows the nozzle of Fig. 7 in axial section.

45 Fig. 9 is a view like Fig. 4 showing an alternative embodiment of my invention.

Fig. 10 is a cross-sectional view of the boiler shown in Fig. 9, taken as indicated by the angled arrows X—X in the latter illustration; and

Fig. 11 is a detail cross-sectional view taken 50 as indicated by the angled arrows XI—XI in Fig. 9.

The locomotive illustrated in Figs. 1—6, for convenience of exemplifying my invention in one form, is generally of well known construction having a horizontal boiler 1 with a firebox 2 at its

rear end. As ordinarily, the firebox 2 is set apart within the boiler shell by a crown sheet 3, side sheets 4, a front sheet 6, rear (door) sheet 7 and a bottom sheet 8, the latter terminating short of said rear sheet to provide the opening 9 for the grate 10. Disposed crosswise of the frontal portion of the firebox is an arch 11 whereof the component fire bricks are supported by a plurality of laterally spaced forwardly declining water tubes 12 which extend longitudinally of the boiler between the rear and front walls and between portions 13 and 14 of the water jacket of the boiler. The firebox 2 is in communication with the stack 15 at the front end of the locomotive by way of usual lengthwise extending fire tubes which are partially shown at 16, in Fig. 6. At each side of its front end the locomotive has an engine cylinder 17 which is operated in a well known way by high-pressure steam, conducted under throttle control from the boiler 1 by suitable piping, not illustrated. The slide valve of the engine operates in an upward offset cylindrical chest 18 integral with the cylinder, which latter has a passage 19 (Fig. 3) by way of which the waste or exhaust steam is conducted to the exhaust nozzle 20 (Fig. 1) and then to the stack 15.

The means, with which the present invention is more especially concerned, for injecting part of the combustion-supporting air above the grate 10, is composed of parts which are duplicated at opposite sides of the locomotive. As instanced in Figs. 1, 4 and 5, each such means includes a plurality of short tubes 21 which extend through the jacketed side wall of the firebox 2 and afford openings through which the air is inducted into said firebox. In the present embodiment there are eight such tubes at each side of the locomotive, disposed in the rear part of the firebox 2 below the plane of the arch 11. The number of the tubes 21 may, of course, be varied in practice in accordance with the size and capacity of the firebox 2, and may be placed above as well as below the arch 11, or nearer the front of the firebox 2. The arrangement is such that the air is led laterally from opposite sides of the firebox 2 into the combustion gases as the latter emanate from the fuel bed on the grate 10 and pass upwardly and forwardly around the rear edge of the arch 11. The air so introduced is thus thoroughly and intimately co-mingled with the gases as they pass over the top of the arch 11 and into the flue tubes 16. Preferably the corresponding tubes 21 at opposite sides of the firebox are offset slightly relative to each other rather than placed in coaxial alignment so that a more effective mixing of the air and the gases is attained. Mounted over the induction end of each tube 21 is an outwardly flared annulus 22, see Figs. 7 and 8, from the interior of which a series of circumferentially spaced radial fins 23 converge outwardly to support a blast nozzle 24 of elbow configuration whereof the inwardly directed horizontal portion is co-axial with the tube 21. As shown in Fig. 8, the nozzle unit just described is of composite construction with its component parts welded together and with the annulus 22 secured to the outer shell of the boiler also by welding as at 25. Set into the open end of the horizontal portion of the nozzle 24 is a removable plug 26 with plural jet apertures 27 which diverge toward the tube 21. Extending along each side of the locomotive 1 is a conduit means in the form of a pipe main 28 having upward branches 29 which lead to the inlets of the nozzles 24, the forward end of said

pipe main being connected as shown in Figs. 1-3 into the passage 19 through which the exhaust steam flows from the valve chest 18 of the cylinder 17 to the exhaust nozzle 20 and the stack 15. Interposed in the pipe main 28 adjacent the nozzle branches 29 is a valve 30 which through suitable connections (not shown) can be controlled from the cab of the locomotive, and adjacent its forward end is an expansion joint 31, see Figs. 1 and 3. In order to prevent glare through the air tubes 21 from interfering with the vision of the engine man, a shield means 32 is mounted over the air inlet units, said shield being provided with a hinged damper 33, which, like the valve 30, can be regulated from the cab of the locomotive by suitable connections (not shown).

From the foregoing it will be seen that part of the exhaust steam leaving the cylinders 17 is conducted by the pipe mains 28 to the nozzles 24 at opposite sides of the locomotive, and utilized to promote air flow into the rear end of the firebox 2 above the fuel bed, by way of the tubes 21. The opposing air streams thus injected laterally into the combustion gas flow, as the latter passes upwardly and forwardly around the rear edge of the arch 11 as shown in Fig. 6, supplement the air drawn upwardly through the grate 10 under forced draft by the suction induced as the remaining portion of the exhaust steam passes upwardly through the exhaust nozzle 20 and the stack 15. The air injected into the firebox 2 above the grate 10 is used to burn the combustible gases which rise from the surface of the fuel bed with the result that sufficient air for complete combustion of the fuel is assured. At the same time the quantity of air passing upwardly through the fuel bed from beneath is greatly reduced so that the smaller fuel particles are not lifted and carried away unburned. The rate of combustion will obviously increase with increase in power, but a substantially constant ratio between the quantities of air entering the firebox 2 respectively from below and above the grate 10 will be maintained, provided the settings of the valves 30 and of the dampers 33 are not disturbed. On the other hand, it is possible for the engine man to change the proportioning of the two air streams by adjusting the valves 30 and/or the dampers 33, as occasion may require.

As an alternative, the steam for the nozzle groups at opposite sides of the locomotive may be supplied from but one of the engine cylinders 17, if this should be found more convenient or desirable in practice.

In the modified embodiment of my invention shown in Figs. 9-11, a housing 32a extends over the air inlet tubes 21a at each side of the firebox 2a; and connecting into the front end of said housing is a tapering trunk 34 which leads downwardly and forwardly at an inclination and has a horizontal end portion which terminates in a group of air inlets 22a whereof there are four in the present instance. Individually associated with the air inlets 22a are nozzles 24a which are generally like the nozzles 24 of the first described embodiment, and which receive exhaust steam through branch pipes 29a of a main 28a from the cylinder (not shown) at the corresponding side of the locomotive.

It will be noted in this case there is a greater number of inlet tubes 21a of smaller diameter than in the first embodiment, with a few of them located above the plane of the arch 11a at each side of the firebox 2a. As a consequence, the air

introduced into the firebox 2a above the grate 10a is somewhat more effectively distributed in said firebox. A larger number of smaller tubes could, of course, be used in the first embodiment, but the additional amount of piping and larger number of steam jets required would tend to unduly complicate matters.

The construction and appurtenances of the modification are otherwise the same as those of the first embodiment, and the component parts thereof not specifically referred to are identified by the same reference numerals previously employed except for the addition to each of them of the exponent "a" for the purposes of more ready distinction. The operation of the modification and the results attained are also like those which characterize the first form so that a separate description is here deemed unnecessary.

As a further modification, a single inlet with a correspondingly larger jet nozzle may be employed in lieu of the four shown in the arrangement of Fig. 9.

Having thus described my invention, I claim:

1. An auxiliary air supply system for a locomotive boiler having a fire box at the rear end with an arch therein which terminates short of the back wall of said box, said auxiliary air supply system including groups of air inlet openings extending respectively through the opposite sides of the boiler into the fire box and communicating into the passage between the arch and said back wall at different levels both above and below the plane of said arch; and injector means for inducing forced flow of atmospheric air from the exterior through the openings into the fire box.

2. An auxiliary air supply system according to claim 1, in which the air inlet openings of both groups are directed at a downward inclination toward the fire bed in the fire box.

3. An auxiliary air supply system according to claim 1, in which the injector means are in the form of nozzles individually associated with the respective openings receiving steam under pressure from the engine of the locomotive.

4. An auxiliary air supply system according to claim 1, in which the air inlet openings at opposite sides of the fire box are axially staggered in relation to each other.

5. An auxiliary air supply system according to claim 1, further including shields which are spaced from the side walls of the fire box and which extend over the two groups of air inlet openings to prevent glare from the interior of said fire box from interfering with the vision of the engineman.

6. An auxiliary air supply system for a locomotive boiler having a fire box at the rear and with an arch therein terminating short of the back wall of said box, said auxiliary air supply system including groups of air inlet openings which extend through the opposite sides of the boiler into the fire box and which communicate into the passage between the arch and said back wall at different levels; injector means for inducing forced flow of atmospheric air from the exterior through said openings into the fire box; shields spaced from the side walls of the firebox providing air passages from the atmosphere to the openings and extending over the respective groups of said air inlet openings to prevent glare from the interior of the fire box from interfering with the vision of the engineman; and regulatable means operatively associated with the shields and adapted to regulate the passages for controlling the

amount of air admitted to the fire box by way of said openings.

7. An auxiliary air supply system for a locomotive boiler having a fire box at one end; plural air inlet openings extending through the opposite sides of the boiler into the fire box; injector nozzles for inducing forced air flow through said openings; shields supported in spaced relation to the sides of the fire box over the respective groups of the air inlet openings to prevent glare from the fire box from interfering with the vision of the engineman; and pipes along the opposite sides of the locomotive for conducting exhaust steam rearwardly from the front of the locomotive, said pipes having branches which extend upward behind the shields to the respective nozzles.

8. An auxiliary air supply system for locomotive boilers in which there is a fire box at one end, said system including groups of air inlet openings extending through the opposite sides of the boiler into the fire box above the normal level of the fire bed in said box; open ended conduits extending along opposite sides of the locomotive from over the regions of the air inlet openings; and means for forcibly injecting pressure fluid into the open ends of the conduits to induce air flow into them from the exterior.

9. The invention according to claim 8, in which the means for inducing the air flow comprises injector nozzles supplied with steam from the engine of the locomotive.

10. The invention according to claim 8, in which the air inlet openings at opposite sides of the fire box are staggered relative to each other.

11. The invention according to claim 8, in which the fire box has an arch; and in which the air inlets are disposed in planes both above and below the level of the arch in the region of the passage between the rear edge of said arch and the back of the boiler.

12. The invention according to claim 8, in which the conduits are provided at their open ends with plural flared mouths; and in which the injecting means include a group of nozzles for injecting the flow inducing fluid into the mouths of said conduits.
